(57) CLAIM

The ornamental design for a multi-strap robe, as shown and described.

DESCRIPTION

FIG. 1 shows a front elevation view of a multi-strap robe; FIG. 2 shows a rear elevation view of the multi-strap robe; FIG. 3 shows a front elevation view of the multi-strap robe in an opened state;

FIG. 4 shows a front elevation view of the multi-strap robe in an alternative opened state;

FIG. 5 shows a left elevation view of the multi-strap robe;

FIG. 6 shows a right elevation view of the multi-strap robe;

FIG. 7 shows a top plan view of the multi-strap robe; and,

FIG. 8 shows a bottom plan view of the multi-strap robe. That which is represented by broken lines illustrates portions of the multi-strap robe that do not form part of the claimed invention.

1 Claim, 7 Drawing Sheets
